CLAIM

The ornamental design for a server device with sequential light display, as shown and described.

DESCRIPTION

The patent file contains at least one drawing executed in color. Copies of this patent with color drawings will be provided by the Office upon request and payment of the necessary fee.

FIG. 1 is a front view of a server device with sequential light display showing our new design at a first point in the sequence;

FIG. 2 is a front view thereof at a second point in the sequence;

FIG. 3 is a front view thereof at a third point in the sequence;

FIG. 4 is a front view thereof at a fourth point in the sequence;

FIG. 5 is a front view thereof at a fifth point in the sequence;

FIG. 6 is a front view thereof at a sixth point in the sequence;

FIG. 7 is a front view thereof at a seventh point in the sequence;

(Continued)

FIG. 8 is a front view thereof at an eighth point in the sequence;

FIG. 9 is a front view thereof at a ninth point in the sequence;

FIG. 10 is a front view thereof at a tenth point in the sequence;

FIG. 11 is a front view thereof at an eleventh point in the sequence;

FIG. 12 is a front view thereof at a twelfth point in the sequence;

FIG. 13 is a front view thereof at a thirteenth point in the sequence;

FIG. 14 is a front view thereof at a fourteenth point in the sequence;

FIG. 15 is a front view thereof at a fifteenth point in the sequence;

FIG. 16 is a front view thereof at a sixteenth point in the sequence; and,

FIG. 17 is a front view thereof at a seventeenth point in the sequence.

The dashed broken lines in the figures illustrate portions of the server device that form no part of the claimed design.

The appearance of the light display sequentially transitions between the images shown in FIGS. 1-17.

The subject matter in this patent includes a process or period in which an image changes into another image. This process or period forms no part of the claimed design.
